UNITED STATES PATENT OFFICE.

CHARLES FRANCIS JENKINS, OF WASHINGTON, DISTRICT OF COLUMBIA.

GAS-ENGINE STARTER.

Specification of Letters Patent. Patented Dec. 17, 1912.

1,047,527.

Application filed November 11, 1910. Serial No. 591,797.

To all whom it may concern:

Be it known that I, CHARLES FRANCIS JENKINS, citizen of the United States, residing at Washington, District of Columbia, have invented certain new and useful Improvements in Gas-Engine Starters, of which the following is a specification.

This invention relates to that class of apparatus known as gas engine starters, and 10 consists primarily of a pump for an elastic fluid and a distributor therefor.

One of the objects of the invention is the design of such a combination as will permit of starting and stopping the pump without disturbing the "timing" of the distributor.

Another object is the selection of such a design of the rotor of the distributor that it will have practically no friction when not actually in use, and yet seat itself without 20 leaking when the fluid is turned onto it.

After trying a great many different forms of distributor valves, the present one has been found so superior to other types as to be rather striking. The tapers with a more 25 sharp angle tend to wedge themselves into the body of the distributor, while the flat ones tend to develop leaky "spots." The distributor of this application seats itself tightly without bringing undue strain on the 30 rotating mechanism and continues tight in use.

In the drawings, Figure 1 is a sectional view of the apparatus, on the line $\alpha-\gamma$ of Fig. 2; Fig. 2 is a front view of the distributor with the cap removed; Fig. 3 is a view of the clutch for connecting and disconnecting the pump; and Fig. 4 a diagram of the parts in use.

Like symbols refer to like parts, in which— 40 A is a pump cylinder; D a piston therein; C a crank for reciprocating the piston; D the crank-shaft, to which is fixedly attached the single-tooth ratchet E. Mounted loosely on the hub of the ratchet E, is a gear F having a pawl G mounted therein to engage with the single-tooth E' (Fig. 3) of the ratchet E. The gear F is prevented from working off the end of the hub of E by a collar E''. To the gear F is attached a yoke 45 H into which the stem I of the rotor J, of the distributor K, fits, being pinned thereto. Shaft D and shaft I are integral. The 50 body of the distributor K has four openings

K' therein, shown dotted in Fig. 2, communicating with the passages K'', which latter, 55 by proper piping (not shown), lead to the 1st, 3rd, 4th and 2nd cylinders, respectively, as this type of engine is usually made. The distributor has a gas-tight cap fitted thereto, having an opening therein adapted to receive a pipe from a source of compressed 60 fluid, as R, in Fig. 4. The rotor J has a single opening therein, so located as to pass over and coincide in succession with the four 65 openings in the distributor body.

It will be observed that, as the shaft D is not rotated by the gear F except as the pawl G engages with the tooth E', the gear F may rotate freely without imparting motion to the pump. However, as the gear F is fixedly 70 attached to the rotor J, through the yoke H, rotary motion is imparted to the rotor at all times. And if the gear is twice the size of the gear on the engine shaft (not shown), with which it is in engagement through intermediate gears, as in rotating electric timers, it (J) will rotate in time with the power 75 strokes of the engine. That is, the distributor is always in time with the engine, while the pump may be thrown into and out of 80 action as the pressure in the tank may require it, automatically or by hand.

The operation of the device, obvious to those skilled in the art, is as follows: The reservoir R having been charged with carbureted gas in any preferred manner, as by 85 hand or by means of the pump shown herein, and it is desired to start the engine, the valve S is opened permitting the compressed gas to flow through the distributor to the second 90 cylinder of the engine (as the distributor stands in Fig. 2). This will push the piston down, and, if the spark is set late, explode the charge as the spark is made, suddenly 95 accelerating the movement of the piston causing it to take up its regular cycle with the least amount of the compressed gas in the reservoir.

No novelty is claimed in the clutch, as any suitable form of device for engaging and 100 disengaging the separate parts thereof, would answer as well as that form shown. Nor is it essential whether the pump be single or multiple cylinder; any convenient form which will pump up the pressure is acceptable.

What I claim, therefore, is—

In apparatus of the class described, the combination with a pump casing, plunger, and actuating crank shaft having an end projecting from the casing, of a rotary distributor supported upon said end with its shaft telescoping the same and revoluble thereon, power devices acting between the pump casing and the terminal face of said

end to rotate the distributor shaft, and means for at will causing the distributor shaft to rotate the crank shaft.

In testimony whereof I have affixed my signature in presence of two witnesses.

CHARLES FRANCIS JENKINS.
